UNITED STATES PATENT OFFICE.

LESLIE A. COOPER, OF SPRINGFIELD, MASSACHUSETTS, ASSIGNOR OF ONE-THIRD TO ALVAH H. SABIN, OF NEW YORK, N. Y.

ROTARY ENGINE.

SPECIFICATION forming part of Letters Patent No. 655,201, dated August 7, 1900.

Application filed October 27, 1899. Serial No. 734,902. (No model.)

To all whom it may concern:

Be it known that I, LESLIE A. COOPER, a citizen of the United States of America, and a resident of Springfield, in the county of 5 Hampden and State of Massachusetts, have invented certain new and useful Improvements in Rotary Engines, of which the following is a full, clear, and exact description.

This invention relates to improvements in 10 rotary engines and rotary compressors for air or other elastic fluids and principally, although not in all respects, to compound concentric-piston rotary engines.

The main object of the invention is to devise 15 an engine of the class mentioned which will be composed of a minimum number of simple and comparatively-cheap and easily-constructed parts, that will be very durable and capable of being run a long time with the avoidance 20 of any considerable or detrimental wear or deterioration, and which above all will serve to utilize the steam economically and at the same time acquire a very high efficiency.

Another object of the invention is to so construct 25 the engine, especially as regards the rotary pistons and abutments thereof, as to avoid all disadvantageous effects of expansion of the rotary pistons and abutments longitudinally, whereby these parts might bind or become cramped in the engine-case.

Another object of the invention is to provide 30 means to reinforce the intermediate portion of the shaft or arbor on which the rotary abutments are carried, so that the tendency of the steam employed within the engine to deflect the abutment-shaft at its middle portion may not result in a hard running of the engine and in undue wearing of the running parts.

The invention consists in a steam-engine 35 having the parts composing it or employed in conjunction therewith constructed and combined or arranged substantially as hereininafter described, and set forth in the claims.

Reference is to be had to the accompanying 40 drawings, in which my invention is exemplified in the form of a novel triple-expansion engine, and in which—

Figure 1 is substantially a central longitudinal 45 sectional view through the engine case and bearings for the rotary piston-shaft and

the shaft of the rotary abutments, the said shafts and the parts carried thereby being seen in side elevation. Fig. 2 is a vertical cross-sectional view as taken on the line 2 2, 55 Fig. 1, looking in the direction of the arrow. Fig. 3 is a vertical cross-sectional view of the engine as taken on the line 3 3, Fig. 1, which intersects one of the rotary and one of the non-rotating partitions separating the first 60 steam-chamber from the next. Fig. 4 is a view somewhat similar to Fig. 3, but taken on the line 4 4, Fig. 1. Fig. 5 is a longitudinal vertical section of the engine-case minus the end heads and with all the internal parts 65 removed, as taken on the plane indicated by the line xx , viewed in the direction of the arrow 5. Fig. 6 is a sectional view similar to Fig. 5, but comprising only the upper portion of the engine-case, as seen in vertical section 70 on the same line xx , Fig. 2, but viewed in the direction of the arrow 6. Fig. 7 is a horizontal sectional view of the upper portion of the engine-case, as taken on the line 7 7, Fig. 2, and looking upwardly. Fig. 8 is an end 75 elevation of the engine. Fig. 9 is a plan view of the same, a portion thereof, comprising the oil-separator, being shown in horizontal longitudinal section. Fig. 10 is a perspective view designed to facilitate the description herein- 80 after given of the peculiar construction of the parts designed with reference to assuring the course of the steam successively into and away from the three steam-chambers of the engine. Fig. 11 is a side view of the rotary appliance 85 comprised in the oil-separating apparatus. Figs. 12, 13, and 14 are perspective views of details of constructions comprised in the oil-separator.

Similar characters of reference indicate corresponding parts in all of the views.

In the drawings, A represents the casing or chambered body of the engine, having at the lower portion the cylindrical space a , extending from end to end, and at the upper 95 portion the cylindrical space a^2 , also longitudinally extending and open along its length to the space a .

The motor-body is cast with a suitable base and is formed screw-threaded at the opposite 100 ends of the opening a for the reception of the opposite end heads a^3 , the upper portions

of which are formed recessed or cut away, as seen at 10 in Fig. 8, each on an arc of a circle, and these recessed portions 10, together with the internal end portions of the walls of the space a^2 , are screw-threaded for the reception of the heads a^4 , which close the space a^2 within the upper portion of the motor-casing.

The end-closing heads a^3 and a^4 are constructed with concentric outwardly-extending hubs and are formed with concentric openings for bearings for the journal-shafts B and C of the rotary pistons and the rotary abutments.

15 As shown, the rotary shaft B has at its opposite ends the circular flanges 10 and 13, which fit peripherally closely and yet for free rotary movements therein the internal wall of the cylinder-space a , and between the said 20 flanges or disks are the flanges or disks 11 and 12 to similarly fit the space a in the casing. The said flanges 10, 11, 12, and 13, in part form partitions transversely dividing the space within the motor-body into several 25 chambers P, S, and T, the completion of the dividing-partitions being constituted by the blocks or castings b^{10} , b^{11} , b^{12} , and b^{13} , all having the form of a major crescent and fitted in the upper cylinder-space a^2 , each with its 30 reentrant arc-shaped edge 15 in contact on and conforming to the periphery of the flange, of which it is an edgewise continuation, the said piston-shaft flanges constituting rotary partitions, while the said parts b^{10} , b^{11} , b^{12} , and b^{13} 35 constitute the completing chamber-separating stationary-partition sections.

The piston-shaft B has between the rotary partition-flanges the cylindrical piston-body or supporting portions 16, of considerably-less 40 diameter than the partition-flanges, radially extending from which are the piston blades or wings p , s , and t , each extending from the one flange to the next and each having its radial extent corresponding to that of all of 45 the rotary partition-flanges.

On the shaft C, which extends freely through openings 17 therefor in the stationary partition-sections, are fixed the "rotary abutments," as termed in this class of engine, 50 the same being respectively indicated by the reference-letters p^2 , s^2 , and t^2 , each of which is in the form of a cylinder having a size to fit the space a^2 in the engine-body and each having the recess 19 at its edge, so that the 55 rotary abutments, which are geared at i , rotate once to every rotation of the rotary pistons will have recesses 19 in positions to leave unobstructed the passage of the piston-blades when the latter come around adjacent the rotary abutments.

c indicates the steam-inlet port, which leads through an upper portion of the engine-body near its end portion, within which is the primary steam-chamber P between the rotary 60 partitions 10 and 11, and, as here shown, the point of entrance of the inlet-port is about at the junction of the one side of the main cyl-

inder-space a with the supplemental space a^2 for the rotary abutments, and at about the same height as inlet-port c , but at the opposite side of the engine-case, is a passage d , the same having a spiral course or one which is in part circumferential around within the internal wall inclosing said space a^2 and which also has a longitudinal trend, so that while the one end 21 thereof leads from the chamber P its opposite end 22 terminates within the space a^2 on the inner wall of the casing that is covered by the stationary partition b^{11} , which is cored out, as shown in Figs. 1, 3, and 10, to 70 constitute the passage 23 for the steam exhausted from the primary cylinder-chamber P.

The passage 23 in the stationary abutment b^{11} , opposite where it registers or communicates with the exhaust-port 22 of the primary steam-chamber P, registers or communicates with the port or terminal 24 of the passage e , which also is formed within the thickness of the wall of the casting composing the engine-body, the same having a spiral course—that is, it extends around to have its opposite end enter the secondary steam-chamber S, a longitudinal trend being given thereto.

The steam in the chamber S after impingement against the piston-wings therein to drive the same around and after the same has made the greater part of a revolution leaves the steam free to be exhausted from said chamber S through the exhaust-port at the terminal of 95 the passage d^2 , opening to which is the passage 25, formed within the stationary partition b^{12} above and edgewise against the rotary partition 12, said passage 25 at the opposite side of the case communicating with the duct or 100 channel f , which because of its curved and also longitudinal progression opens into the third steam-chamber T at the same side of the engine-body at which the steam had been 105 admitted into the primary and secondary steam-chambers, and properly oppositely-arranged is the exhaust-port g , through which 110 is discharged the steam which has been used expansively the third time in the chamber T.

It will be noted that the engine-casing in 115 the plane of and above the stationary partition b^{12} , which has the passage 25 therethrough, as aforesaid, also has the duct or channel 26, of approximately-semicircular form as to its length, which as well also as the said passage 120 25 leads to communication with the aforesaid passage f , the longitudinal trend of which carries it offset from the plane of the rotary and stationary partitions 12 and b^{12} to open 125 into the tertiary steam-chamber T. This construction augments the transferring-passage from the secondary to the last steam-chamber to accord with the volume of the steam which has expanded in the secondary chamber to much greater volume than it had acquired 130 when it entered such chamber.

Viewing Fig. 10 and regarding the arrows c^* , e^* , and f^* as corresponding to and having approximately the relative positions of

the ducts or passages *c*, *e*, and *f* within the internal wall of the engine-case at one side thereof and the arrows *d*^{*}, *d*^{**}, and *g*^{*} as corresponding to and having approximately 5 the relative arrangement of the conduit ducts or passages *d*, *d*², and *g* at the other side of the upper portion of the engine-casing, the manner of the successive action of the steam against the several rotary pistons in this compound triple-expansion rotary engine will be 10 more easily understood.

As the engine has been designed and constructed by me the space circumferentially within the engine-case around in which the 15 pistons rotate comprises between the entrance-passages for the steam into the steam-chambers *P*, *S*, and *T* and the passages *c*, *e*, and *g*, opposite thereto, through which the steam is carried out of such chambers, some- 20 what less than a quarter of the internal circumference of the wall inclosing the space *a*, and hence the piston *s*, in the secondary steam-chamber *S*, is set about a quarter ahead of the piston *p* in the first chamber *P*, so that 25 about as piston *p* shall have fairly passed exhausting-port *d* for its steam-chamber, whereby the steam from such chamber is transferred into the secondary chamber *S*, the said piston *s* will have fairly passed the inlet-opening 30 for the secondary steam-chamber, and so again the piston *t* is set so far in advance of the second piston *s* that just about as that piston is passing the exhaust-port of the secondary chamber, whereby the steam is dis- 35 charged into the last steam-chamber, the said piston *t* will have fairly passed the steam-entrance port leading into the said steam-chamber *T*, each of the succeeding pistons receiving the impetus of the steam which has been 40 exhausted from the preceding steam-chamber, but the force of which has not been dissipated.

The end heads *a*³ and *a*⁴ of the engine-casing, provided with the axially outwardly extended hubs 31, are constructed with comparatively-deep circular openings 30 therein, having the annular shoulders 32, extending centrally through which openings are the extremities of the piston and rotary abutment-shafts *B* and *C*.

33 represents an annular ball-cup fitted against the seat at the inner end of the said circular opening 30, adjacent which is the double cone-ended sleeve 34, and between the 55 one beveled or conical end and the adjacent ball-cup are the hardened balls 35. The said sleeve is loose on its shaft and comprised between the outer beveled or conical end of said sleeve and a second ball-cup 33, suitably adjacent, is a second series of hardened balls 35, the location of the latter being somewhat within the outer end of the opening, which latter is internally screw-threaded for the reception 60 therein of the externally-threaded annular plug 36, having an internal inner end annular shoulder and which part 36 is also internally threaded for the reception of

the supplemental ring-plug 37, which is loose about the shaft and together with the part 36 constitutes the stuffing-box for the shaft. 70

38 represents a lock-nut which screws upon the exterior of the said part 36, which is extended endwise beyond the hub 31 of the casting-head *a*³ or *a*⁴, as the case may be, and serves to lock the bearings after the same have 75 been adjusted by crowding the said threaded part 36 to place the cups, balls, and end cones of the sleeve in properly-close relations.

It will be perceived that the end rotary partitions 10 and 13 of the piston-shaft and also 80 the end stationary partitions *b*¹⁰ and *b*¹³ are arranged slightly distant from the end heads of the engine-case and that all of the stationary partitions, both at the ends of and between the rotary abutments, may have endwise compensating movements as may be imparted thereto by the expansion or contraction axially of the parts mounted on the piston-shaft and the parts mounted on the rotary abutment-shaft, and that any endwise extension or contraction of the piston or rotary abutment shafts will be without effect to either lock up and cause binding or an undue loosening in the ball-bearing journals, owing to the fact that the shafts may have slight 95 endwise play through the sleeves, which latter, nevertheless, are so closely fitted on the shaft that they rotate as one therewith, so that the ball-bearings support the weight of the running parts and receive the friction in 100 the journals therefor.

Inasmuch as the engine-case will expand and contract about equally with the moving parts therewithin there is no greater difficulty derived from expansion and contraction between the parts in peripheral contact or proximity than there is between the pistons and cylinders of any engine, and binding of the parts peripherally is overcome in this engine in part by the fact that weight of the running 110 parts is entirely supported within the journals at the end heads and because, furthermore, I have made provision whereby such impact of the steam as may come transversely relatively to the rotary abutments and which through them may be transmitted to the rotary abutment-shafts is resisted. The provision to this end consists in providing one of the stationary partitions (the one, *b*¹², which is as near the middle of the engine as practicable) interiorly with a recess 40, in which is received the saddle 42, having the rollers 43 43 journaled therein and which are peripherally in contact with the said shaft *C*, which passes loosely through the said partition *b*¹², 115 and a threaded plug 44, which screws through the top of the motor-casing and has its lower portion passed loosely through an opening therefor in the upper wall of the cored-out stationary partition and bears by its lower 120 end against the top of the saddle. This reinforces the rotary abutment at its central portion, where there would be the greatest liability that the steam-pressure would deflect 125 130

it to result in carrying the adjacent faces of the abutment and rotary partitions out of coinciding planes and otherwise the shaft out of alinement. The steam is finally exhausted through port *g* into the end of the longitudinally-ranging cylindrical chamber *G*, comprised within the casting which forms the engine-case and in which are appliances, to be next described, for separating the oil introduced with the steam into the engine from the exhaust-steam. The said chamber has end heads to constitute journal-bearings for the shaft *50*, surrounding which is the tubular core *52*, having a multiplicity of perforations *53*, in which are anchored a corresponding number of radial wires *54*, extending to or near to the internal wall of the chamber *G*.

At suitable intervals along the length of the brush-like appliance are ring-plates *h*, preferably formed in half-sections, with angularly-turned lips *55*. These ring-plate sections are supported by arms *56*, carried by sectional hubs *57*, which are clamped about the core *52* by the screws, bolts, or rivets *58*.

Along the base of the casing, in which is the chamber *G*, is the channel *59*, the same downwardly opening at one end thereof to the oil-receiver *H*, while at the end of the casing *G* opposite that at which the steam is exhausted thereinto is the final steam-discharge conduit *60*.

The shaft *50* is driven by the externally-applied gearing *62* *63*, shown as run from the rotary-abutment shaft-gear *j*.

The admixed steam and oil entering the initial end of the casing *G* is caused by the ring-plate to necessarily mainly pass along through the brush near its core. The mist-like particles of oil are arrested by and collected on the wires and by the centrifugal action thereof thrown outwardly against the surrounding wall of the chamber *G* and run down to the bottom thereof into the channel *59* and thence into the receiver *H*. As the steam will have a tendency to work toward the wall of the chamber, the succession of the ring-plates are provided at suitable intervals, as before mentioned, to constitute a steam-break, so that it will have its course diverted several times toward the core of the brush to give all portions of the latter opportunity to exert its oil-collecting action before the steam passing through the chamber *G* reaches the final discharge-passage *60*.

In addition to the rotary wires or collecting members I may also employ non-rotary wires or collecting members, which may be advantageously supported in and extended upwardly above the base of the drain-channel *59* into the chamber *G* and lapping by the ends of the revolute wires, vacant places being left in the brush-like appliance to accommodate these stationary wires or projections. The purpose of these stationary wires or projections will be explained as follows: The steam after having entered within the brush-wires will after awhile have developed a rev-

oluble motion more or less nearly in consonance therewith, whereby the beating action by the brush-wires on the steam and the oil elements therein becomes lessened.

The provision of the stationary wires or members projecting from the wall of the case well toward the core of the brush constitute not only additional parts against which the steam will impinge and upon which deposit more or less of the contained oil, but will counteract and lessen the revolute and centrifugal motion of the steam, whereby the latter in its continued course through the brush-wires will be by the latter more efficiently whipped and will consequently insure that the said brush-wires will collect thereon a greater proportion of the oil which is held in suspension by the steam passing there-through.

Inasmuch as the engine herein described has been constructed with reference to its capability for utilization as an air-compressing engine or compressor for other compressible fluids or gases, attention is therefore directed to the fact that air introduced into and having its substantially-spiral course through the engine in the reverse direction from that described for the steam will by the revolute pistons, which by their rotations in a direction opposite that imparted thereto by the expanding steam, compress the air first in the large chamber *T*, again to a further lessened volume in chamber *S*, and a third time to a still decreased volume in the chamber *P*, the so-compressed air passing from the last compression-chamber through the port *c*.

Having thus described my invention, what I claim, and desire to secure by Letters Patent, is

1. In a rotary concentric-piston compound steam-engine, the chambered engine-case having therein a shaft provided with several separated rotary partition-flanges, and therebetween piston-wings extending from the one flange to the other, and a second shaft having the rotary abutments, the lengths of which correspond to the spaces between the rotary partition-flanges, and non-rotary partitions between the rotary abutments, complementary to and arranged edgewise adjacent the rotary partitions, all said rotary partitions and rotary abutments being contained in and peripherally fitting the internal wall of the single engine-case, a steam-inlet passage leading into the steam-chamber comprised between the first two rotary partitions, a discharging-passage for that chamber leading therefrom and entering a succeeding steam-chamber within the said casing and an exhaust-passage for such latter steam-chamber.

2. In a rotary concentric-piston compound steam-engine, the chambered engine-case having therein a shaft provided with several separated rotary partition-flanges, and therebetween piston-wings extending from the one flange to the other, and a second shaft having the rotary abutments, the lengths of which

- correspond to the spaces between the rotary partition-flanges, and non-rotary partitions between the rotary abutments, unattached to the engine-casing and free for compensating movements longitudinally of the engine, and arranged edgewise adjacent the rotary partitions, all said rotary partitions and rotary abutments being contained in and peripherally fitting the internal wall of the single engine-case, a steam-inlet passage leading into the steam-chamber comprised between the first two rotary partitions, a discharging-passage for that chamber leading therefrom and entering a succeeding steam-chamber within the said casing and an exhaust-passage for such latter steam-chamber.
3. In a concentric-piston rotary steam-engine, an engine body or casing comprising the partially-cylindrical space a and the adjoining partially-cylindrical space a^2 , the one being open to the other and having opposite end heads with journals, parallel longitudinally-ranging shafts journaled in said end heads, and capable of endwise compensating movements therein, the one shaft having separated rotary partition-flanges peripherally fitting the internal wall of said space a , the outer faces of said flanges adjacent the inner sides of the end heads being separated therefrom and the other shaft having a rotary abutment running between two of the rotary partition-flanges, a piston-wing extending between the rotary partitions and constituting a movable wall of the steam-chamber comprised between such flanges, a steam-inlet passage and a steam-outlet passage leading to and from the steam-chamber, for the purposes set forth.
4. In a concentric-piston rotary steam-engine, an engine body or casing comprising the partially-cylindrical space a and the adjoining partially-cylindrical space a^2 , the one being open to the other and having opposite end heads with journals, parallel longitudinally-ranging shafts B and C , journaled in said end heads, and capable of axial compensating movements therein, the one shaft having separated rotary partition-flanges peripherally fitting the internal wall of said space a , the outer faces of said flanges adjacent the inner sides of the end heads, being separated therefrom, and the other shaft having a rotary abutment running between two of the rotary partitions, the unattached non-rotary partitions of crescent shape edgewise fitting the peripheries of the rotary partition-flanges, a piston-wing extending between the rotary partitions and constituting a movable wall of the steam-chamber comprised between such flanges, a steam-inlet passage and a steam-outlet passage leading to and from the steam-chamber, for the purposes set forth.
5. In a concentric-piston rotary compound steam-engine, an engine-casing having the spaces a and a^2 extending from end to end, and having a series of steam-inlet ports arranged along one internal portion of said cas-
- ing and steam-outlet ports arranged along a suitably-distant internal portion of the casing, parallel shafts, one carrying piston-wings and the other abutments, partitions between coöperating pairs of the piston and abutments, which separate the steam-chambers, into and from each of which one of the inlet and outlet ports communicate, and unvalved or ever-open and unobstructed passages leading from the outlet-port of a primary steam-chamber into the inlet-port of a secondary steam-chamber, for the purpose set forth.
6. In a concentric-piston rotary compound steam-engine, an engine-casing having the spaces a and a^2 extending from end to end, and having a series of steam-inlet ports arranged along one internal portion of said casing and steam-outlet ports arranged along a suitably-distant internal portion of the casing, parallel shafts, one carrying piston-wings and the other abutments, partitions between coöperating pairs of the pistons and abutments which separate the steam-chambers, into and from each of which one of the said inlet and one of the said outlet ports communicate, and unvalved or ever open and unobstructed passages leading from the outlet-port of a primary steam-chamber into the inlet-port of a secondary steam-chamber, the piston-wings revolving in a secondary chamber being set in advance of the piston-wing in the steam-chamber primary thereto, for the purpose set forth.
7. In a compound rotary concentric-piston engine, an engine case or body constructed for and receiving the piston-shaft B having several separated rotary partition-flanges with partition-wings extending from the one flange to another, and the rotary abutment-shaft C having rotary abutments lapping by, and entering the spaces between the rotary partition-flanges wherein are comprised the steam-chambers, an inlet for the first steam-chamber leading thereinto, an outlet-port leading from said steam-chamber and continued in a substantially-spiral direction and terminating in a suitably-opposite port entering the next succeeding steam-chamber.
8. In a compound rotary concentric-piston engine, the engine-case having journal-supported thereby the piston-shaft B and a rotary abutment-shaft C , the first having a plurality of piston-wings and the second respectively coöperating rotary abutments, partitions dividing the spaces in which the piston-wings revolve one from another constituting together with the engine-case separate steam-chambers, means for introducing and exhausting the steam into and from the several chambers successively, and adjustable means for reinforcing the middle portion of the abutment-carrying shaft against being deflected by the steam-pressure transverse thereto.
9. A compound rotary concentric-piston engine, comprising the engine-case and the journal-supported piston-shaft B with rotary

piston-wings and the rotary abutment-shaft with the rotary abutments coöperating with said wings, and suitable chamber-dividing transverse partitions, a saddle carrying the 5 rollers in bearing against an intermediate part of the rotary abutment-shaft, and a screw threading through the engine-case and setting against the saddle at the side of the said shaft opposite the steam-chamber in the 10 engine, for the purpose set forth.

10. In a compound rotary engine, comprising shafts having several piston-wings, and coöperating rotary abutments, partitioning means between the pistons and abutments, 15 whereby the separate steam-chambers are comprised within the engine-case that is in common to, and incloses all the rotary pistons and corresponding rotary abutments, a steam-passage leading into the primary steam-chamber, 20 and passages continued from each steam-chamber, to each succeeding steam-chamber whereby the steam is caused to pursue a practically-helical course through the engine for successive expanding actions against the 25 piston-wings in the respective chambers therefor.

11. In a rotary engine, the end heads thereof having centrally-apertured hubs through which the shaft of the engine extends which 30 is provided with the closely-fitting but unattached sleeve cone-formed at both its ends, the series of balls provided to support the inner conical end of the sleeve, a second series of balls and a ball-cup outside thereof provided in the hub-opening on which balls the outer conical end of the sleeve is supported, the annular screw-plug 36 threading into the outer end portion of said apertured hub against said ball-cup, and serving to adjust 35 the same and a locking-nut on the outer end thereof, all whereby endwise expansion of the shaft may be without effect to change the adjusted conditions of the said ball-bearing.

12. An engine-case, having spaces each of 45 the form of a portion of a cylinder and the one along its length open to the other, longitudinally-ranging parallel shafts, piston-wings on one shaft and rotary recessed abutments on the other shaft, stationary partition- 50 sections between the rotary abutments, and in the planes thereof disks concentric with the piston-shaft which divide the chambered engine-case into separate steam-chambers, an inlet-opening entering the primary steam-chamber, and an outlet-passage leading from 55 each steam-chamber into the chamber secondary thereto.

13. In a compound concentric-piston rotary engine, the combination with the engine-casing 60 constructed with the longitudinally-extending spaces a and a^2 each comprising a portion of the cylinder and opening the one to the other, the rotary piston-shaft having the rotary partitions 10, 11, and 12, whereby 65 separated primary and secondary steam-chambers are constituted within said casing,

the non-rotary partitions b^{10} , b^{11} , and b^{12} arranged in the planes of and adjoining said rotary partitions, the one b^{11} having the passage 23 therethrough which opens to the opposite edges thereof which are in contact against opposite sides of the wall of said space a^2 , the port leading through the engine-casing at one side into the primary chamber, a port formed within the internal wall of the 70 casing at the opposite side of the primary steam-chamber, and continued around and also endwise to connect with the one end of said passage 23, a port formed in the casing in communication with the other end of said passage and continued around, and also endwise, and terminating in the secondary steam-chamber and a steam-discharging opening 75 for said secondary chamber, substantially as described.

14. In a compound concentric-piston rotary engine, the combination with the engine-casing constructed with the longitudinally-extending spaces a and a^2 , each comprising a portion of a cylinder, and opening the one to 90 the other, and provided with the steam-inlet port c and other ports e and f which are continued in passages having a course around and also endwise along within the inner wall of the said space a^2 , the rotary piston-shaft having the rotary partitions 10, 11, 12, and 13, fitted within the said space a and the non-rotary crescent-shaped partitions b^{10} and b^{13} , and the non-rotary partitions b^{11} and b^{12} which have the passages 23 and 25 therein which open 95 at the opposite edges thereof, said passages each at its one end matching with the passages continued from said ports e and f , the piston-wings p , s , and t , and the corresponding rotary abutments p^2 , s^2 , and t^2 , and means 100 for rotating them and said casing furthermore having the ports d and d^2 opening at the inner portion of the chamber a^2 covered by the said non-rotary partitions b^{11} and b^{12} , and having communication with the passages therein 105 and having endwise courses and terminating in the second and third steam-chambers, and an exhaust-passage for the third steam-chamber, substantially as described.

15. In a rotary engine, an engine body or 115 casing having partially-cylindrical spaces therein, opening the one to the other, and extending to the end of the casing, and an end closure for the engine-casing comprising a head of circular form fitted at the end of the 120 one partially-cylindrical space, and having a curved recess in its edge, and a cylindrical head fitted at the end portion of the other cylindrical space and also matching in the curved recess of the first-named head.

16. In a rotary engine, the engine body or 125 casing having the partially-cylindrical spaces therein opening the one to the other, and extending to the end of the casing, and an end closure for the engine-casing comprising a head of circular form screw-threading in the 130 end of the one partially-cylindrical space and

having a curved threaded recess in its edge, and a circular head, screw-engaged in the threaded end portion of the other cylindrical space, and in the curved and threaded recess of the first-named head, and said parts so constructed as to provide an annular shoulder or seat inside of the marginal face of each of the said closing heads between which seat and

the corresponding head an annular packing may be interposed. ¹⁰
